CLAIM

The ornamental design for the combined depilation wax applicator and base, as shown and described.

DESCRIPTION

FIG. 1 is a 3/4 front perspective view of the combined depilation wax applicator and base showing my new design; FIG. 2 is a 3/4 front perspective view from the right side showing the base alone for clarity and completeness of disclosure. The left view is symmetrical;

FIG. 3 is a 3/4 rear perspective view from the right side showing the base alone. The left view is symmetrical;

FIG. 4 is a 3/4 front perspective view from the right side showing the applicator element of the design separately and with its cap removed for clarity and completeness of disclosure. The left view is symmetrical;

FIG. 5 is a 3/4 rear perspective view from the right side showing the applicator and the cap separated; and,

FIG. 6 is an enlarged scale top view showing the applicator without its cap.

The undisclosed bottom surfaces of the applicator, base and cap form no part of the claimed design.
